No. 37,311.

Patented January 31, 1905.

UNITED STATES PATENT OFFICE.

BERNE NADALL, OF KINGSTON-UPON-THAMES, ENGLAND, ASSIGNOR TO LINOTYPE AND MACHINERY, LIMITED, OF LONDON, ENGLAND.

DESIGN FOR A FONT OF MATRICES.

SPECIFICATION forming part of Design No. 37,311, dated January 31, 1905.

Application filed October 11, 1904. Serial No. 228,058. Term of patent 14 years.

To all whom it may concern:

Be it known that I, BERNE NADALL, a citizen of the United States, residing at Kingston-upon-Thames, in the county of Surrey, England, have invented a new, original, and ornamental Design for a Font of Matrices, of which the following is a specification, reference being had to the accompanying drawings, forming part thereof.

10 The two figures of the drawings represent face or plan views of the two matrices constit-

tuting the font. These matrices are of the same design, one being simply the reverse of the other.

What I claim as new, and desire to secure 15 by Letters Patent, is—

The ornamental design for a font of matrices, as shown.

BERNE NADALL.
